[57] CLAIM

The ornamental design for a paint tray with removable handle, as shown and described.

DESCRIPTION

FIG. 1 is an exploded perspective view of a paint tray with removable handle showing my new design;

FIG. 2 is a top view thereof;

FIG. 3 is a side sectional view thereof, taken along line 3—3 in FIG. 2, the other side being a mirror image;

FIG. 4 is a front partial sectional view thereof, taken along line 4—4 of FIG. 2; and,

FIG. 5 is a rear view thereof, as seen in the direction of line 5—5 of FIG. 2.

The broken line showing is for illustrative purposes only and forms no part of the claimed design.
